CLAIM

The ornamental design for a photoprocessor, as shown and described.

DESCRIPTION

FIG. 1 is a perspective of a photoprocessor embodying our new design, looking at the front and right side thereof.

FIG. 2 is a top view looking in the direction of arrows 2—2 of FIG. 3.

FIG. 3 is a left side view of FIG. 1.

FIG. 4 is a front view looking in the direction of arrows 4—4 of FIG. 3.

FIG. 1.

FIG. 2.
